UNITED STATES PATENT OFFICE.

HARRY A. LEWIS, OF NORRISTOWN, PENNSYLVANIA.

METHOD OF AND APPARATUS FOR GRINDING COMMUTATOR BRUSHES.

Application filed October 31, 1924. Serial No. 747,042.

My invention relates to a method of and apparatus for grinding commutator brushes and the like, and more particularly to a method and means whereby the contacting 5 surfaces of the brushes may be ground to the curvature of different sizes of commutators, and whereby the body of the article may have the proper angularity with respect to the said contacting surfaces.

10 Heretofore it has been the usual practice to effect proper contact between a commutator brush and its commutator by interposing a sheet of sand paper or the like between the brush and the commutator, or by simply 15 placing a brush in operative position and permitting it to wear to the proper contour. Both these methods are unsatisfactory because, in the first place, the operation is slow and tedious and particles of abrasive become 20 lodged in the insulation and the brush is usually not closely shaped to the contour of the armature until after it has been in use for some time. In the second instance, where the brush is shaped through contact 25 with the commutator, a great deal of sparking occurs and a considerable deposit of particles from the brush during the early stage of grinding finds its way into the crevices of the commutator.

30 My invention has for one of its objects the provision of a means and a method whereby the brushes may be conveniently and accurately formed to fit commutators of different diameters, before placing them in operative 35 position.

Another object of my invention resides in the provision of a means and a method whereby accurate measurements of the commutator and the angularity of the brush with respect thereto may be obtained, and the measurements utilized in adjusting a 40 machine for grinding the brushes.

Still another object of my invention is to provide a grinding machine for commutator 45 brushes, of improved form.

Some of the forms which my invention may take are shown in the accompanying drawings, wherein Fig. 1 is a view of a grinding machine embodying my invention, 50 in side elevation; Fig. 2 is a plan view thereof; Fig. 3 is an elevational view looking from the left of Fig. 1; Figs. 4 and 5 are side elevational and plan views, respectively, of a modified form of grinding machine; 55 Fig. 6 is a view showing a tool employed for

measuring the curvature of a commutator and the angularity of the brush with respect thereto; and Fig. 7 is a view showing a scale whereby a reading of the results obtained as shown in Fig. 6 may be secured.

While I herein show and describe my invention as employed in connection with the shaping of commutator brushes, it will be apparent that it may be useful in other relations.

Referring now to Figs. 1 to 3, 8 indicates the fixed base of a machine upon which a bearing structure 9 may be mounted for adjustment longitudinally of the base, by means of bolts 10 carried by the support 9 and having their shanks and heads fitting within T-slots in the base 8. A carriage 11 is pivotally mounted upon the support 9 through the medium of a pair of bearings 70 12 of a slide 14.

The carriage 11 is provided upon its lower surface with a pair of ribs 13 of dove-tail form that mesh with grooves in the slide 14. The carriage is movable longitudinally of the slide by means of a screw 15 which is rotatably mounted in bearings 16 that project downwardly from the carriage 11. The screw 15 is rotated by a handle 17 and has threaded engagement with a nut 18 which is secured to the underside of the slide 14.

The screw 15 is held against longitudinal movement with respect to the bearings 16, so that as it is rotated the carriage 11 will be moved longitudinally of the bed 8.

Upon the forward end of the carriage 11 I provide an extension 19 for supporting an electric motor 20 and a grinding wheel 21 that is driven from the motor 20 through the medium of a belt 22.

The carriage 11 is rotatable about the 95 bearings 12 by means of a screw 23 that is provided with a handle 24. The screw has threaded engagement with a nut 24^a that is pivotally mounted and that has a bearing pin 25 projecting therefrom as shown in Fig. 3, and is thereby pivotally supported in a boss or bearing block 26 projecting upwardly from the base 8. The shank of the screw 23 passes through a bearing 27 with which it is rotatably associated, but wherein it is held against longitudinal movement. The bearing 27 is pivotally supported by the slide 14 in a manner similar to the support for the nut 24^a.

From the foregoing it will be seen that the 110

grinder is adjustable in two directions, (a) through an arc about the pivots 12, and (b) in a direction longitudinally of the base 8. This latter adjustment is normally effected by means of the screw 15, but for wider ranges of adjustment the bolts 10 may be loosened and the bearing block 9 slid along the base 8.

The grinder 21 is mounted for operation upon a carbon block or brush 27 which may be mounted in a holder 28, the block or brush 27 being clamped in position therein by means of a screw 29. The holder 28 is movable vertically by a screw 30 which engages a nut 31 carried by the holder 28, and is rotatably supported but held against longitudinal movement, by a bracket 32. The bracket 32 is slidably supported upon a block 33, by means of a screw 34 that is rotatable in the block 33 and has threaded engagement with a nut 35 which is secured to the bracket 32.

The block 33 is pivotally mounted at 36 upon the base 8 and is adjustable about said pivot by means of a clamping bolt 37 carried by the block and an arcuate slot 38 provided in the base.

By reason of the form and arrangement of the supporting structure just referred to, the brush 27 may be moved to various positions with respect to the grinder 21. For instance, the block 33 may be adjusted about its pivot 36 to vary the angle of the brush with respect to the grinder 21, in a radial direction. The bracket 32 may be adjusted toward and from the grinder 21 to effect the proper depth of cut and the holder 28 may be adjusted vertically to effect the proper angularity of cut across the front of the brush.

When the brush has been given the desired adjustment with respect to the grinder, the motor 20 may be operated to rotate the grinder and the grinder caused to move across the face of the brush by operating the screw 23 to oscillate the carriage 11 about its pivots 12.

Referring now to Figs. 4 and 5, I show a grinding machine of different form than that just described.

In this instance I provide a base 41 upon which a standard 42 is adjustably mounted by means of bolts 43 that are secured to the standard 42 and fit within T-slots in the base 41. At its upper end the standard 42 is provided with a bearing block 45 which is pivotally supported by means of a pin 46. The block 45 is slotted at 44 to receive a bracket arm 47 that may be adjustably positioned therein by means of a set screw 48. At its outer end, the arm 47 supports a bracket 49 that carries a brush holder 50 which is vertically adjustable therein in a manner similar to the holder 28 in the bracket 32. A brush 27 is mounted in the

holder 50. The bracket 49 is adjustably mounted upon a slide block 51 that is in turn adjustable about a pivot 52.

It will be seen that the arm 47 corresponds in some respects to the carriage 11 of Fig. 1, but that I have mounted the brush or carbon block on said arm instead of mounting the grinder and motor thereon.

The grinder 53 is mounted upon an upright 54 that is rigidly secured to the base 41 and is driven by a belt 55 from any desired source of power.

In Fig. 4 the adjustments of the brush 27 with respect to the grinder 53 are effected in substantially the same manner as in the case of Fig. 1, but instead of moving the grinder bodily with respect to the brush, I move the brush and permit the axis of the grinder to remain stationary. This movement of the brush is effected by means of a screw 56 whose lower end is rotatably supported in a bearing 57 but held against longitudinal movement therein, that is secured to the base 41. The screw 56 engages with a nut 58 that is pivotally mounted upon the arm 47. The mounting of the bearing 57 and the nut 58 may be similar to the mounting of the members 24 and 27 in Fig. 3.

The arm 47 is not intended to be movable longitudinally, but the standard 42 is movable along the base 41 to change the location of the pivotal point 46 longitudinally of the arm, thus varying the radius of the curve in which the brush 27 will move when the arm is oscillated by the screw 56.

In Figs. 6 and 7 I show means whereby a radial measurement may be obtained to serve as a guide for effecting the adjustment of the arms 11 or 47 with respect to their pivots, to provide the desired arc of movement as between the brush holder and the grinder.

In Fig. 6, 61 represents a commutator, 62 a measuring instrument provided with projections 64 and with a hole for the reception of a pin 65 that may be positioned therein by a set screw 66. A plate 67 is pivotally mounted upon the instrument 62.

In order to determine the curvature of the commutator, the instrument 62 is placed thereagainst, with the members 64 in engagement therewith, and the end of the pin 65 is also brought into engagement with the periphery of the commutator. The plate 67 is then laid against the side of the brush 27 to measure the angularity thereof. When the measurements have been thus secured the tool 62 is placed upon a chart as shown in Fig. 7. The inner end of the projections 64 and the pin 65 are placed adjacent to the curve with which they most nearly coincide. The radius of these curves is indicated in inches and fractions of inches, as shown. The angularity of the plate 67, and hence of the brush, is determined by the radial lines

that are marked to indicate degrees. For instance, if it is desired to duplicate the brush 27 of Fig. 6, the measuring instrument is applied to the commutator 61 in the manner shown and caused to engage with the brush. The positions of the movable parts 65 and 67 of the measuring instrument 62 are maintained and such instrument applied to the chart of Fig. 7. In the instance shown, the commutator is indicated as having a radius of $2\frac{1}{2}$ " and the brush as having an angle of 25° .

With the readings thus provided through application of the tool to the chart of Fig. 7, the position of the grinder 21 with respect to its pivot 12 is so adjusted that the face of the grinder will move in an arc two inches radially distant from the pivot 12, and therefore corresponding to the curvature of the commutator 61, in order to grind a curved contacting surface on the brush 27 that will accurately fit the commutator. Similarly, the brush holder 28 may be adjusted vertically in order that the curve ground therein will be properly disposed with respect to the longitudinal center line of the brush, and the bracket 32 may be tilted about the pivot 36 to an angle corresponding with the 25° angle of the plate 67.

A similar procedure will be followed in the case of the machine in Figs. 4 and 5, except that the radial position of the brush with respect to its pivot 46 will be adjusted, since in that structure the grinder 53 is mounted upon a fixed axis.

Various changes in detail and general arrangement may be made without departing from the spirit and scope of the invention as defined in the accompanying claims.

40 I claim as my invention:

1. The method of grinding commutator brushes, which comprises providing a

grinder holder and a brush holder, one of which is pivotally mounted, that are angularly adjustable with respect to one another, 45 ascertaining the desired angular position of the brush with respect to the commutator and the curvature of the commutator, adjusting the relative angular positions of said holders to correspond with the first-named 50 angular position, and adjusting the position of the pivotally mounted holder radially of its pivot to correspond with the curvature desired on the contacting face of the brush, and imparting relative movement to said 55 holder to grind the brush.

2. Apparatus for grinding commutator brushes and the like, comprising a cutting tool holder, a brush holder, means for moving said tool holder through an arcuate path, 60 means for adjusting the position of said holder radially of its pivot, a brush holder for supporting a brush in position for endwise engagement with said tool, and means for adjusting said brush holder tangentially 65 of the path of pivotal movement of said tool.

3. Apparatus for grinding commutator brushes and the like, comprising a cutting tool holder, a brush holder, means for moving said tool holder through an arcuate path, 70 means for adjusting the position of said holder radially of its pivot, a brush holder for supporting a brush in position for endwise engagement with said tool, means 75 for adjusting said brush holder tangentially of the path of pivotal movement of said tool, and means for adjustably positioning the brush holder about an axis that is parallel 80 to the axis of movement of the tool holder.

In testimony whereof I, the said HARRY A. LEWIS, have hereunto set my hand.

HARRY A. LEWIS.
